FIG 7

HIS ATTORNEY

UNITED STATES PATENT OFFICE.

STEFANUS NIELSEN, OF NEW YORK, N. Y., ASSIGNOR TO THE MONARCH TYPEWRITER COMPANY, OF SYRACUSE, NEW YORK, A CORPORATION OF NEW YORK.

TYPE-WRITING MACHINE.

No. 889,955.

Specification of Letters Patent.

Patented June 9, 1908.

Application filed March 2, 1905, Serial No. 248,062. Renewed May 27, 1907. Serial No. 375,882.

To all whom it may concern:

Be it known that I, STEFANUS NIELSEN, a subject of the King of Norway, and resident of the borough of Brooklyn, city of New York, in the county of Kings and State of New York, have invented certain new and useful Improvements in Type-Writing Machines, of which the following is a specification.

10 My invention relates more particularly to the ribbon mechanism of that class of type-writing machines employing a ribbon vibrator or carrier, by which term is meant any device for moving the ribbon to cover and uncover the printing point.

One object of my invention is to provide a construction wherein a ribbon having a plurality of fields of different characteristics may, at printing operation, be moved to cover the 20 printing point with any desired field of the ribbon.

Another object is to provide means to dispense at will with the crosswise feed of the ribbon in that class of machines employing a 25 ribbon vibrator and wherein the ribbon has both a crosswise and a lengthwise feed.

A further object is to provide means to enable a ribbon of more than one color to be employed in the last named class of machines.

Another object is to dispense at will in such machines with the vibratory movement of the ribbon.

To the above and other ends the invention 35 resides in the features of construction, arrangements of parts and combinations of devices to be hereinafter more fully described and particularly pointed out in the appended claims.

40 In the accompanying drawings, Figure 1 is a vertical front to rear sectional view, taken about centrally, of one form of type-writing machine embodying my invention. Fig. 2 is a fragmentary front elevation showing the upper portion of the machine. Fig. 3 is a rear view taken on a plane represented by the line *x* in Fig. 1, various parts being omitted. Fig. 4 is a fragmentary top plan view showing parts of the ribbon mechanism. 45 Figs. 5, 6 and 7 are enlarged top plan views similar to Fig. 4 but showing various parts in different positions from those in which they appear in said Fig. 4. Fig. 8 is a top plan view of a modified construction of one of the 55 elements hereinafter called a cam member.

My invention is shown as embodied in a Monarch typewriting machine but it may be adapted to other forms of writing machines.

In the drawings, 1 is the base of the machine supporting corner posts 2, which sustain a top plate 3. Key levers 4 are fulcrumed on a fulcrum plate 5 and each key lever is provided with a restoring spring 6. Pivoted at 7 to each key lever is a sub-lever 8, the lower portion whereof co-acts with a 65 fixed abutment 9 and the upper portion whereof is connected by a link 10 with a type bar 11 which is one of a segmentally arranged series. Each type bar 11 is seated in a radial slot 12 formed in a segmental type bar support 13, the heels of the type bars being perforated to receive a segmental pivot wire 14 which is contained in a groove cut in the top face of the segmental support 13. Instead of this mode of pivoting the type bars on a 70 fulcrum wire said bars may be provided with 75 separate hangers and pivots.

The type bars are normally supported at their outer ends by a segmental type rest 15 and said bars are adapted to co-operate with a 80 platen 16 mounted in a carriage 17, said carriage being guided and supported by anti-friction balls 18 which are seated in grooved rails 19 on the carriage and in oppositely grooved rails 20 mounted on brackets 21 85 which are fixedly secured to the top plate 3.

The carriage 17 is provided with a feed rack 22 which normally meshes with a pinion 23, the latter being operatively connected with an escapement wheel 24. Adapted to 90 co-operate with the escapement wheel are feed dogs 25 mounted on a pivoted dog rocker 26 which has a horizontal arm 27 connected by a rod or link 28 with the rearwardly extending arm 29 of a universal bar 95 frame 30 pivoted in the base of the machine at 31. The frame 30 carries a universal bar 32 which extends from side to side of the machine beneath the spacing levers (not shown) and the series of key levers 4, and is adapted 100 to be actuated by said levers when the latter are depressed, as happens during each printing or spacing operation. The carriage 17 is connected by a strap 33 with a spring drum 34 which tends to draw the carriage to the 105 left so that when the universal bar 32 is actuated the escapement mechanism just described is caused to be operated in a known manner and thereby to permit of letter space movements of the carriage.

Ribbon spools 35 arranged above the top plate 3 at each side of the machine and forwardly of the platen, receive a ribbon 36, which, as herein shown, is divided longitudinally into fields *a* and *b* of different characteristics, that is to say, the field *a* may be of one color such as black, and the field *b* of another and different color such as red, or the field *a* may be copying ribbon and the field *b* record ribbon, etc. The ribbon 36 may be fed longitudinally from either spool to the other by any suitable means. The drawings illustrate a ribbon feed mechanism which is similar to that employed in the Monarch typewriting machine and which is explained in U. S. patent to Jacob Felbel & Carl Gabrielson No. 703,339, dated June 24, 1902. Each ribbon spool 35 is carried by and turns with an upright shaft 37 which rotates in a fixed bearing 38 and has secured at its lower end a small beveled gear 39. The gear 39 meshes with a beveled pinion 40 secured to the forward end of a horizontal shaft 41, which shaft carries at its rear end a beveled pinion 42 which is adapted to mesh with a beveled driving pinion 43 mounted on a driving or power shaft 44. Rotary movement is transmitted to the shaft 44 by beveled pinions 45 and 46, the pinion 45 being operatively connected with the driving shaft 44 and the pinion 46 with the spring drum 34.

It will be understood that both ribbon spools are connected with similar gear trains which are adapted to be actuated from driving pinions 43 on the driving shaft 44. As explained in the above cited patent the driving or power shaft 44 is capable of longitudinal movement, and it is further to be understood that the longitudinal position of said shaft determines which driving pinion 43 will be in mesh with its co-operating pinion 42 and which ribbon spool will be turned to wind the ribbon thereon.

Midway between the ribbon spools the ribbon 36 is threaded through a ribbon vibrator or carrier 47 which is guided and supported in the upright arms 48 of a supporting bracket 49, the latter being secured to the top plate by screws 50. The lower portion 50 of the vibrator 47 is slotted and provided with a crosswise pin 51 which engages with the slotted forward end of an operating lever 52 pivoted at 53 in a lug 54 depending from the under side of the top plate. The rear arm of the operating lever 52 is formed with an elongated slot 55 having at its forward end a downwardly extending portion 55^a. Engaging with this slot 55 is a pin or stud 56 carried by and secured in the top of a link 57, the lower end of said link being pivoted at 58 to the rear arm 29 of the universal bar frame. The link is provided near its upper end with a forwardly and downwardly bent arm 59. The link 57 is adapted to be swung about its pivot 58 in order to cause the stud

56 to move longitudinally of the slot 55 so as to engage the operating lever 52 at varying distances from the pivot or fulcrum 54 and thereby to vary the throw of the ribbon carrier or vibrator 47. This swinging or vibratory movement of the link 57 is caused by an eccentric controller or member 60 which is slidably mounted upon the driving shaft 44 and which is adapted to co-operate with the strap formed by the link 57 and its bent arm 59. The eccentric controller 60 comprises a comparatively narrow eccentric working face 61, a tapered or cam portion 62 and a sleeve portion 63, the latter being formed with a circumferential groove or depression 64. A screw 65 passes into the sleeve portion 63 of the member 60, and enters an elongated slot or groove 66 in the driving or power shaft 44. The eccentric member 60 is thereby slidably connected with the power shaft 44 and is caused to rotate with said shaft but may be moved longitudinally of the shaft without affecting the latter. The shaft 44 may also be moved longitudinally without affecting the member 60. The longitudinal movement of the eccentric member 60 is controlled by a switching member or slide 67 which comprises, first, a vertically disposed arm 68 terminating at the top in a perforated collar portion 69 and at the lower end in a fork 70 which partially surrounds the depression 64 and the member 60; and second, a horizontally disposed arm 71 extending rearwardly from the vertical arm 68. As seen in Figs. 3 to 7 inclusive, the arm 71 comprises a rearwardly extending portion 72, a portion 73 at right angles thereto and parallel with the driving shaft 44, an obliquely disposed and forwardly extending portion 74, a short portion 75 parallel with the portion 73, another and shorter obliquely disposed and forwardly extending portion 76, and, finally, another short portion 77 parallel with the portions 73 and 75. The pull and push rod 78 has its inner end fixedly secured in the collar portion 69 of the switching member or slide 67 and bears in the flange of the top plate 3, passing through the latter and terminating exteriorly of the machine in a finger button 79. The rod 78 is formed with notches or depressions 80, 81, 82 and 83 with which a locking spring 84 is adapted to engage, said locking spring being secured to the top plate by a screw 85. The rod 78 also has a bearing in a lug 86 depending from the top plate, which lug serves also as one of the bearings of the driving shaft 44. Depending from the central rear portion of the top plate is an elongated pin 87 to which is secured the rear end of a coiled spring 88, the forward end whereof is attached to the link 57. The spring 88 constantly tends to draw the link 57 rearwardly so as to cause the stud 56 to engage with the rear end of the slot 55.

If a one-color ribbon is in use on the machine and it be desired to employ a two-color ribbon, the latter may be substituted for the one color ribbon in a known manner. 5 With the two color ribbon in place and the parts positioned as shown in Figs. 3 and 4, the ribbon will be fed progressively cross-wise during successive printing operations and some of the type impressions will be 10 made on the field *a* which may, for example, be black in color, other impressions will be made on the field *b* which may, for example, be red in color, while yet other impressions will be made partly on one field and partly 15 on the other. By this mode of operation a variegated or party-colored effect may be obtained which may be desired in some styles of ornamental typewriting. In most forms of typewriting, however, it is desirable 20 to print in one color at a time. If as suggested the two color ribbon be, as is most usual, a black and red ribbon, and it be desired to print only on the black field, the pull rod 78 is drawn outward (or to the left as 25 viewed in Figs. 3 to 7, inclusive) until the locking spring 84, which normally is in engagement with the first notch 80 engages with the second notch 81. As the rod 78 moves to the left it carries with it the switching member 67, and the eccentric member 60 30 participates in this movement by reason of the connection formed by the engagement of the fork 70 with the depression 64 of said eccentric member. The leftward movement 35 of the switching member disengages the eccentric face 61 from its strap and permits the spring 88 to draw the link 57 backward so that the pin or stud 56 is maintained thereafter at the rear of the slot 55. 40 The parts will now be positioned as indicated in Fig. 5, and at each depression of a key lever 4 the ribbon vibrator will be raised to the same height. The mechanism is so proportioned and adjusted that this movement 45 of the ribbon vibrator causes the black field *a* to always cover the printing point and the path of the type impressions will be in a straight line longitudinal of the ribbon field *a*. 50 If it be desired to print upon the red field *b* of the ribbon the rod 78 is drawn still further outward or to the left until the spring 84, disengaging from the notch or depression 81, engages with the notch 82. Drawn by the rod 78 the switching member is moved 55 still further leftward. It will be noted upon an inspection of Fig. 5 that at the beginning of this new movement the link 57 is at the elbow formed by the junction between the portions 73 and 74 of the arm 71 of the 60 switching member 67. As the switching member moves to the left the oblique portion 74, acting on the link 57, cams said link forward longitudinally of the lever 52 and against the pull of the spring 88 and forces 65 the link upon the short portion 75 against

which the said link is maintained by the pull of the spring 88. The parts will now be positioned as indicated in Fig. 6, the pin or stud 56 being towards the front of the slot 55 of the operating lever 52 and nearer to the fulcrum 53 of said lever. So positioned, each depression of a key lever 4 will cause the ribbon vibrator to be raised to the same height, and the mechanism is so proportioned and adjusted that this constant throw 70 of the ribbon vibrator will bring the red field *b* to the printing point and the path of the type impressions will be in a straight line longitudinal of said ribbon field *b*. 75

At times it may be desired to maintain the 80 vibrator quiescent in normal position so that a stencil may be prepared for mimeograph work without the interposition of the ribbon between the type and platen at each printing operation. To accomplish this result the 85 pull rod 78 is pulled out still further to the left until the locking spring 84 engages with the last notch 83 in said rod. The switching member 67 is drawn with the rod 78 still further outward or to the left and the oblique 90 portion 76 of the arm 71 acting upon the link 57 cams said link still further forward longitudinally of the lever 52 and forces the link upon the portion 77 of said arm 71, against which portion the link is maintained 95 by the pull of the spring 88. The parts will now be positioned as indicated in Fig. 7 wherein it will be noted that the stud 56 has been moved forward still further in the slot 55 of the operating link 52 so 100 that said stud will now be above the downwardly extending portion 55^a of the said slot. At each depression of a key lever 4 the link 57 is drawn downwardly, carrying with it the stud 56, the latter moving downward in the forwardly extending portion 55^a of the slot 55. The parts are so proportioned that the stud 56 reaches the limit of its downward movement before it can contact with the bottom of the downwardly extending or cut away portion 55^a. The result is that the movement of the link 57 does 105 not affect the operating lever 52, so that the latter will remain quiescent as long as the parts are maintained in the last described relation. If the rod 78 be now pushed inwardly or to the right so as to cause the locking spring to successively reengage with the notches 82, 81 and 80, the reverse of the operations hereinbefore detailed will take place 110 and at each key depression the ribbon vibrator will be moved so as to bring either the red field, the black field or progressively the whole width of the ribbon to the printing point according as either the notch 82, the 115 notch 81 or notch 80 be in engagement with the locking spring 84. The tapered face 62 enables the eccentric member to readily find its strap and effect a certain connection therewith. 120 125 130

In Fig. 8 I have illustrated a modification of the means (the arm 71) employed for positioning the link 57 longitudinally of the operating lever 52. Referring to said figure it will be noted that the arm 71 is replaced on the inner end of the slide rod 78 by a cam member 89, said cam member being provided with an open-ended slot comprising a camming portion 90, a dwell portion 91, a 10 second camming portion 92, a dwell 93, a camming portion 94 and a dwell 95. The slot is so proportioned that the front and rear edges of the link 57 will contact slightly with the front and rear walls of 15 the slot so that the said link is positively positioned fore and aft of the machine by the camming member 89. The cam 90 guides the link into the slot and the cams and dwells 91, 92, 93, 94 and 95 correspond 20 respectively to the parts 73, 74, 75, 76 and 77 in the first described form. This modified construction enables the draw spring 88 to be dispensed with.

Various changes in the construction and 25 arrangements of the parts may be effected and parts of the invention may be used without other parts, all without departing from the spirit of my invention.

What I claim as new and desire to secure 30 by Letters Patent, is:—

1. In a typewriting machine, the combination of printing keys, a ribbon vibrator, a single lever for operating said vibrator, a single link movable by the printing keys for 35 operating said lever, means for maintaining said link in a fixed relation with said lever, and means for altering said fixed relation by moving said link longitudinally of said lever.

2. In a typewriting machine, the combination of a ribbon vibrator, a single lever for 40 operating said vibrator, a single means movable longitudinally of and adapted to be set to operate upon said lever at desired distances from its fulcrum, and printing keys 45 adapted to move said single means to operate upon said lever at any one of said distances.

3. In a typewriting machine, the combination of a ribbon vibrator, a single lever for 50 operating the same, a key actuated universal bar, a single link connected with said universal bar, said link being movable longitudinally of and adapted to be set to operate upon said lever at one time to throw said 55 vibrator a predetermined distance and being adapted to be set to operate upon said lever at another time to throw said vibrator a different predetermined distance, and printing keys adapted to move said link.

60 4. In a typewriting machine, the combination of a ribbon vibrator, a single lever for operating the same, a key actuated universal bar, a single link connected with said universal bar, said link being movable longitudinally of and adapted to be set to be opera-

tive upon said lever to throw said vibrator different predetermined distances, printing keys adapted to move said link, and hand actuated means for altering and fixing the predetermined distance to which the vibrator is thrown.

5. In a typewriting machine, the combination of a ribbon vibrator, a single lever for operating the same, a link, means for causing said link to operate automatically upon said lever at progressively increasing and decreasing distances from the fulcrum of said lever, means for throwing out of operative relation said automatic means and for fixing the relation between said link and said lever, and means for altering said fixed relation at will.

6. In a typewriting machine, the combination of a ribbon vibrator, a slotted lever for operating the same, a link provided with a pin adapted to move back and forth in the slot of said lever, an eccentric adapted to coöperate with said link and thereby to control the movement of its pin, means adapted to disconnect the eccentric from the link and to fix the relation between said link and said lever, means for altering said fixed relation at will, and means for actuating said link.

7. In a typewriting machine, the combination of a ribbon vibrator, a single lever adapted to operate the same, a single means for actuating said lever to throw said vibrator different distances, an automatic crosswise ribbon feed mechanism operative in connection with said single means, and hand actuated means whereby the automatic crosswise ribbon feed mechanism is rendered inoperative and the relation between said lever and said single means is fixed, and thereafter the fixed relation between said lever and said single means is altered and said link and said single means are maintained in another and different fixed relation.

8. In a typewriting machine, the combination of a ribbon vibrator, a slotted lever for operating the same, a link provided with a pin adapted to move back and forth in the slot of said lever, an eccentric adapted to coöperate with said link and thereby to control the movement of its pin, a switching member adapted to disconnect the eccentric from the link, said switching member being adapted to move said link longitudinally of said lever towards its fulcrum to different predetermined distances, and thereby to alter the throw of said ribbon vibrator.

9. In a typewriting machine, the combination of a ribbon vibrator, a single lever adapted to operate the same, a single means for actuating said lever to throw said vibrator different distances, an automatic crosswise ribbon feed mechanism operative in connection with said single means, and a hand actuated slide operative upon said single means

to disconnect it from said automatic cross-wise ribbon feed mechanism and to fix the relation between said lever and said single means and thereafter to alter the relation between said lever and said single means and to maintain them positively in another and different fixed relation.

10. In a typewriting machine, the combination of printing keys, a ribbon vibrator, a single vibrator operating lever, a link movable by the printing keys for operating said lever, and means for moving said link longitudinally of said lever to an inoperative position, the operating planes of both link and lever remaining unchanged.

11. In a typewriting machine, the combination of a ribbon vibrator, a single lever for operating said vibrator, a single link acting directly on said lever to vibrate it, means for maintaining said link in a fixed relation with said lever, means for moving said link longitudinally of said lever to another position and thereby altering the fixed relation and for moving said link to still another position longitudinally of said lever and thereby rendering said link inoperative upon said lever, the operating planes of both link and lever remaining unaltered, and means for actuating said link.

12. In a typewriting machine, the combination of a ribbon vibrator, a single lever for operating the same, a key actuated universal bar, and a single link connected with and actuated by said universal bar, said link being operative upon said lever at one time to throw said vibrator a predetermined distance and being operative upon said lever at another time to throw said vibrator a different predetermined distance and being inoperative upon said lever at another time, the movement of said link to so co-act with said lever being always longitudinal of the latter.

13. In a typewriting machine, the combination of a ribbon vibrator, a single lever for operating the same, a key actuated universal bar, a single link connected with and movable by said universal bar, said link being movable longitudinally of said lever to different positions and being inoperative upon said lever in one of said positions and being adapted to throw said vibrator different predetermined distances in the other of said positions, and hand actuated means for rendering said link inoperative and for altering the predetermined distance to which said vibrator is thrown.

14. In a typewriting machine, the combination of a ribbon vibrator, a single lever for operating the same, a link, means for causing said link to operate on said lever at progressively increasing and decreasing distances from the fulcrum of said lever, means for throwing out of operative relation the means to cause said link to operate progressively and for thereafter moving said link longitudinally of said lever both to throw said ribbon vibrator any one of a plurality of predetermined distances and also to render said link inoperative upon said lever.

15. In a typewriting machine, the combination of a ribbon vibrator, a lever for operating the same, said lever being provided with a slot having a downwardly extending portion, a link provided with a pin adapted to move back and forth in the slot of said lever, an eccentric adapted to coöperate with said link and thereby to control the movement of its pin, and a switching member movable to disconnect the eccentric from the link, said switching member being further movable to positively position said link longitudinally of said lever at different predetermined distances from its fulcrum and thereby first to alter the extent of movement of said lever and finally to bring the pin of said link above the downwardly extending portion of the slot in said lever whereby said link is rendered inoperative upon said lever.

16. In a typewriting machine, the combination of a ribbon vibrator, a lever for operating the same, said lever being provided with a slot having a downwardly extending portion, a link provided with a pin adapted to move back and forth in the slot of said lever, an eccentric adapted to coöperate with said link and thereby to control the movement of its pin, a switching member movable to disconnect the eccentric from the link, said switching member being further movable to positively position said link longitudinally of said lever at different predetermined distances from its fulcrum and thereby first to alter the extent of movement of said lever and finally to bring the pin of said link above the downwardly extending portion of the slot in said lever whereby said link is rendered inoperative upon said lever.

17. In a typewriting machine, the combination of a ribbon vibrator, a single lever adapted to operate the same, a single means for actuating said lever to throw said vibrator different distances, a crosswise ribbon feed mechanism operative in connection with said single means, and a hand actuated slide operative positively upon said single means to disconnect it from said crosswise ribbon feed mechanism and to fix the relation between said single means and said lever and thereafter to alter the relation between said link and said single means and to maintain them in another and different fixed relation, and finally to again alter the relation between said lever and said single means so as to render the latter inoperative upon the former.

18. In a typewriting machine, the combination of printing keys; a ribbon vibrator; a

- single lever for operating said vibrator; a single link movable by the printing keys for actuating said lever; and means for positively maintaining said link in any one of a plurality of fixed relations with said lever, said means comprising a cam member adapted to move said link longitudinally of said lever.
19. In a typewriting machine, the combination of printing keys; a ribbon vibrator; a single lever for operating said vibrator; a single link movable by the printing keys for actuating said lever; means for positively maintaining said link in any one of a plurality of fixed relations with said lever, said means comprising a slotted cam plate adapted to move said link longitudinally of said lever; and hand actuated means operable exteriorly of the machine for controlling the position of said cam plate.
20. In a typewriting machine, the combination of printing keys, a ribbon vibrator, a single lever for operating said vibrator, a single link movable by the printing keys for operating said lever, means for maintaining said link against movement longitudinally of said lever when the printing keys are operated, and means for moving said link longitudinally of said lever.
21. In a typewriting machine, the combination of a ribbon vibrator, a single lever for operating the same, a key actuated universal bar, a single link connected with said universal bar, said link being movable longitudinally of said lever and operative thereon to throw said vibrator different predetermined distances, printing keys operative to move said link, and hand actuated means for altering at will the predetermined distance to which the vibrator is thrown.
22. In a ribbon vibrating mechanism for typewriting machines, the combination of a ribbon vibrator, an operating arm, a member connected with said operating arm by a pin and slot connection, and means for setting the pin and slot connection so that the pin will engage at any desired one of a plurality of predetermined points in the slot and for maintaining the parts in set position, thereby enabling the extent of throw of the vibrator to be regulated.
23. In a typewriting machine, the combination of a ribbon vibrator, a key actuated universal bar and connections between said vibrator and said universal bar, said connections including a lever, a link, a pin and slot connection between said link and lever, the pin being adapted to be moved longitudinally of the slot and to be set to operate at different points along the slot, and hand operated means for setting said pin in any one of a plurality of positions along said slot and maintaining said pin in set position.
24. In a ribbon vibrating mechanism for typewriting machines, the combination of a ribbon vibrator, an operating lever connected therewith and provided with a slot, an actuating link provided with a pin engaging said slot, and means for moving said pin longitudinally of the slot and for setting said pin to operate on the lever at different predetermined points in the length of the slot and maintaining said pin in set position.
25. In a ribbon vibrating mechanism for typewriting machines, the combination of a ribbon vibrator, a lever connected therewith for operating said vibrator, an actuating link normally held to engage said lever at a predetermined distance from its fulcrum so as to throw the ribbon vibrator always a given distance, and hand actuated means for moving the link longitudinally of the lever and setting said link in a new position so as to operatively engage said lever at a different predetermined distance from its fulcrum so as to give the ribbon vibrator a different extent of throw.
- Signed at the borough of Manhattan, city of New York, in the county of New York, and State of New York, this 28th day of February, A. D. 1905.
